(57) **CLAIM**

I claim the ornamental design for a contact lens holder having rotating caps with viewing lenses and number indicia for tracking days of usage, as shown and described.

DESCRIPTION

FIG. 1 is a perspective view of a contact lens holder having rotating caps with viewing lenses and number indicia for tracking days of usage, showing my new design;

FIG. 2 is a top plan view thereof;

FIG. 3 is a front elevational view thereof, the rear being a mirror image;

FIG. 4 is a left side elevational view thereof;

FIG. 5 is a right side elevational view thereof; and,

FIG. 6 is a bottom plan view thereof.

1 Claim, 2 Drawing Sheets

FIG. 3

FIG. 4

FIG. 5

FIG. 6
